UNITED STATES PATENT OFFICE.

SAMUEL SEGAL, OF NEW YORK, N. Y.

PADLOCK.

1,387,187.

Specification of Letters Patent. Patented Aug. 9, 1921.

Application filed November 18, 1920. Serial No. 424,822.

To all whom it may concern:

Be it known that I, SAMUEL SEGAL, a citizen of the United States, and a resident of New York, in the county of New York and State of New York, have invented certain new and useful Improvements in Padlocks, of which the following is a specification.

My invention relates to padlocks and 10 more particularly to pin tumbler padlocks.

The principal object of the invention is the production of a padlock of extreme simplicity of construction, of strength and rigidity and which shall contain a minimum 15 number of parts, thereby making for economy and for ease of manufacture and assembly.

Other and further objects and advantages of the invention will appear from the following description, the invention consisting in the novel parts and combinations of parts hereinafter more particularly described and then specified in the claims.

In the accompanying drawings illustrating a practical embodiment of the invention:

Figure 1 is a vertical section (partly in elevation) taken through my improved padlock.

Fig. 2 is a horizontal section on the line 2—2 of Fig. 1.

Fig. 3 is a horizontal section on the line 3—3 of Fig. 1.

Referring in detail to the several figures 35 of the drawing:

1 indicates the hollow body or casing of the padlock provided with bores or openings in the upper wall 1' thereof receiving the long and short legs 2 and 3 respectively 40 of the shackle 4 as in the ordinary construction of padlock. Said long leg 2 is provided with a flanged or beaded end 5 to prevent complete withdrawal of the shackle from the body and both legs are provided 45 with slots 6 adapted to receive locking dogs to be presently described whereby any withdrawal of the shackle from the body is prevented.

7 indicates a pin tumbler barrel provided 50 with the usual rectangular shaped extension 7' integral therewith and constituting the housing for the pin tumbler (not shown). 8 is a face plate or escutcheon preferably integral with said barrel 7 and which fits 55 within the end of the body of the padlock and engages a shoulder 9 thereon. Said

face plate is non-removably fastened or secured in this position when the parts within the padlock are properly assembled. The barrel 7 receives an ordinary conventional 60 key-plug or cylinder (not shown) which is rotatable, one end of which is received by a suitable annular opening in the face plate 8 and the other or inner end of which is provided with a plate 10 engaging the end 65 of the barrel 7 whereby a forward withdrawal of the cylinder through the barrel is prevented. Preferably integral with said plate 10 is a finger 11 bent or turned downwardly and adapted to engage the side of 70 the extension or pin tumbler housing 7' and obviously acting as a stop to limit the movement of rotation of the cylinder within the barrel 7. Connected to the key-plug within the barrel 7 and projecting upwardly 75 therefrom is the stem 12.

13 indicates a rotatable post, preferably hexagonal-shaped or of a shape other than round, provided with a flanged end 14 bearing against the inner surface of the upper 80 wall 1' of the padlock and with an annular opening 15 receiving a lug 16 which is preferably integral with said upper wall and which acts as a pivot on which said post is rotated. 17 are locking dogs or plates 85 having hexagonal-shaped central openings of a size permitting them to receive said post whereby independent rotation of said locking dogs or post with respect to each other is prevented. The upper of said locking dogs 17 engages a shoulder 18 on said post 13 and a washer 19 carried by said post is interposed between said locking dogs as shown in Fig. 1.

A compression spring 20 which encircles 90 said post 13 engages the lower of said locking dogs 17 as well as the plate 10. The function of said spring is not only to retain the flanged end 14 of the post in engagement with the inner surface of the upper wall 1' 95 of the padlock whereby the lug 16 will at all times enter the opening 15 but it acts to retain the locking dogs in the proper vertical position on said post and in alinement with the slots 6 in the legs of the shackle. The end of the post 13 is provided with a slot 21 receiving the stem 12 of the cylinder 100 within the barrel 7.

The padlock may be operated by a suitable key 22 adapted to enter a slot in the 110 key-plug within the barrel 7 to rotate the same in the usual manner in cylinder or pin

tumbler locks, the operation of which is old in the art and well understood. The rotation of said key-plug, inasmuch as connection between the post 13 and key-plug is 5 made by the stem 12 and slot 21, rotates the post, as is manifest, to cause the locking dogs 17 to enter the slots 6 in the legs of the shackle or be withdrawn therefrom so that said shackle may be locked to the body 10 of the padlock or unlocked as desired.

What I claim as my invention is:—

1. In a padlock, a hollow body, a shackle, a rotatable post within said body and a locking dog rotatable with and carried by said 15 post and slideable vertically thereon and adapted to interlock with said shackle.

2. In a padlock, a hollow body, a shackle, a rotatable post within said body carrying locking means adapted to interlock with said 20 shackle, a barrel within said body, a key-plug carried thereby, a plate fastened to one end of said key-plug and adapted to engage the end of said barrel and a finger on said plate adapted to engage the side of said barrel 25 rel to limit the movement of rotation of said post.

3. In a padlock, a hollow body, a shackle, a rotatable post within said body, locking means carried by said post adapted to interlock with said shackle and a spring engaging said locking means for maintaining the 30 same in proper vertical position on said post.

4. In a padlock, a hollow body, a shackle, a rotatable post within said body provided 35 with a slot, a key-plug supported within said body, a stem connected to said key-plug and entering the slot in said post, locking means carried by said post adapted to interlock with said shackle and a spring engaging said key-plug and said locking means 40 for maintaining said locking means in proper position.

5. In a padlock, a hollow body, a lug on said body, a shackle, a rotatable post within 45 said body provided with a slot and with an opening receiving said lug, a key-plug supported within said body, a stem connected

to said key-plug and entering said slot in said post, a locking dog carried by said post adapted to interlock with said shackle and 50 a spring engaging said key-plug and said locking dog.

6. In a padlock, a hollow body, a lug on said body, a shackle, a rotatable post within said body provided with a slot and with an opening receiving said lug, a shoulder on said post, a key-plug supported within said body, a stem connected to said key-plug and entering said slot in said post, a locking dog slidably mounted on said post and engaging 55 the shoulder thereon and rotatable therewith and adapted to interlock with said shackle and a spring encircling said post and engaging said key-plug and said locking dog. 65

7. In a padlock, a hollow body, a lug on said body, a shackle, a rotatable post within said body provided with a slot and an opening receiving said lug, a barrel fastened to said body, a rotatable key-plug within said 70 barrel, a stem connected to said key-plug and entering said slot in said post, a locking dog carried by said post adapted to interlock with said shackle, a spring engaging said key-plug and said locking dog and a 75 finger connected to said key-plug and adapted to engage said barrel to limit the movement of rotation of said post.

8. In a padlock, a hollow body, a lug on said body, a shackle, a rotatable post within 80 said body provided with a slot and with an opening receiving said lug, a key-plug supported within said body, a stem connected to said key-plug and entering said slot in said post and a locking dog carried by said 85 post adapted to interlock with said shackle.

Signed at New York in the county of New York and State of New York this 17th day of November, A. D. 1920.

SAMUEL SEGAL.
